(57) **CLAIM**

The ornamental design for a speaker, as shown and described.

DESCRIPTION

FIG. 1 is a top-left perspective view of a speaker showing my new design;

FIG. 2. is a bottom-right perspective view thereof;

FIG. 3. is a top plan view thereof;

FIG. 4. is a bottom plan view;

FIG. 5. is a right side view thereof;

FIG. 6. is a left side view thereof;

FIG. 7. is a front view thereof;

FIG. 8. is a back view thereof;

FIG. 9. is a top-left perspective view thereof, shown with the top lid in an open condition;

FIG. 10. is a bottom-right perspective view thereof, shown with the top lid in the open condition;

FIG. 11. is a top plan view thereof, shown with the top lid in the open condition;

FIG. 12. is a bottom plan view thereof, shown with the top lid in the open condition;

FIG. 13. is a right side view thereof, shown with the top lid in the open condition;

FIG. 14. is a left side view thereof, shown with the top lid in the open condition;

FIG. 15. is a front view thereof, shown with the top lid in the open condition;

FIG. 16. is a back view thereof, shown with the top lid in the open condition;

FIG. 17. is a perspective cross-section view thereof, taken in the direction of line 17-17 in FIG. 14, shown with the top lid in the open condition;

FIG. 18. is a back cross-section view thereof, taken in the direction of line 17-17 in FIG. 14, shown with the top lid in the open condition;

FIG. 19. is a perspective cross-section view thereof, taken in the direction of line 19-19 in FIG. 14, shown with the top lid in the open condition;

FIG. 20. is a back cross-section view thereof, taken in direction of line 19-19 in FIG. 14, shown with the top lid in the open condition;

FIG. 21. is a perspective cross-section view thereof, taken in the direction of line 21-21 in FIG. 14, shown with the top lid in the open condition;

FIG. 22. is a back cross-section view thereof, taken in the direction of line 21-21 in FIG. 14, shown with the top lid in the open condition;

FIG. 23. is a perspective cross-section view thereof, taken in the direction of line 23-23 in FIG. 11, shown with the top lid in the open condition; and,

FIG. 24. is a back cross-section view thereof, taken in the direction of line 23-23 in FIG. 11, shown with the top lid in the open condition.

(Continued)

The broken lines in the figures illustrate the portions of the speaker that form no part of the claimed design.
